UNITED STATES PATENT OFFICE.

JOHN ALYUSIOUS LEHNERT, OF HOWARD, SOUTH DAKOTA.

FLYING MACHINE.

Application filed November 17, 1922. Serial No. 601,603.

To all whom it may concern:

Be it known that I, JOHN A. LEHNERT, a citizen of the United States, and a resident of Howard, in the State of South Dakota, have invented certain new and useful Improvements in Flying Machines, of which the following is a specification.

This invention relates in general to flying machines, and more particularly to an improvement in the means for propelling, driving or otherwise controlling the flight of such machines.

The object of the invention is to provide a propulsion means which may be advantageously utilized for driving or lifting an aeroplane or other aeronautical apparatus or for maintaining the lateral stability thereof so that during flight and when landing the machine is under the complete control of the pilot or operator.

Accordingly the invention in its broader aspects consists in providing a propeller carrying one or more propeller blades shiftable or adjustable so that the pitch of the blades may be varied, controlling means being provided for carrying out the desired shifting or adjusting of the blades. In one of the preferred embodiments of the invention gravity-controlled means, such as a pendulum or the like, is organized with the controlling means so that the shifting of the propeller blades is automatically effected under the influence of the pendulum. It is especially desirable to employ a pendulum in conjunction with the other elements of the invention when it is sought to control or preserve the lateral stability of the flying-machine and in such an organization propellers are provided at each side of the machine and rotate about a vertical axis, the pendulum being so organized with the controlling means for the shiftable propellers that the pitch of the blades of the propeller at the sides of the machine will be automatically regulated to compensate for tilting or other disturbances of the lateral stability of the ship.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a plan view of an embodiment

of the invention, parts being broken away and parts being shown in section for the sake of illustration;

Figure 2 is a view in side elevation, a section of the propeller casing being removed and parts being broken away and shown in section for the sake of illustration;

Figure 3 is a detail view in elevation of a portion of a propeller blade illustrating the means employed on the propeller blade for adjustably mounting it in the propeller casing;

Figure 4 is a view in section on line 4—4 of Figure 2; and

Figure 5 is a view in elevation, showing an aeroplane having the present invention organized therewith in such manner as to maintain the lateral stability of the plane.

Referring to the drawings, and more especially to Figures 1 to 5 the numeral 10 designates diagrammatically an engine or other power plant from which the propeller shaft 11 is driven by any suitable gearing or motion transmission mechanism. The propeller shaft 11 is squared or of polygonal cross section but intermediate its ends it has fixed thereto a bearing sleeve 12 by which the propeller shaft is rotatably mounted in the bearing 13 provided in a frame member 14 suitably associated with the frame of the aeroplane.

A propeller casing, designated generally at 15 is mounted on the outer end of the shaft 11 and is suitably secured to the shaft so as to be held thereon and constrained to rotate with the shaft. This propeller casing 15 may be made up of a number of sections, preferably two, designated at 16 and 17, the sections being bolted to each other in assembly, as at 18. A number of propeller blades, preferably two, are associated with the casing or frame and are designated at 19 and 20, respectively. Means are provided for mounting the propeller blades in the casing so that these blades are positively constrained to partake of the rotary movement of the casing and shaft while at the same time permitting the blades to be shifted or adjusted about their longitudinal axis to vary the pitch or inclination of the blades. This means may comprise caps 21 and 22 bolted or otherwise suitably secured to the ends of the blades 19 and 20, and each carrying a series of grooved rings, the rings of the cap 21 being designated at 23 and the rings of the cap 22 being designated

at 24. These rings 23 and 24 coat with circular webs 25 and 26 having annular grooves which register with the grooves of the rings 23 and 24 and which together provide races for ball bearings 27 and 28. In order to prevent accidental or endwise displacement of the blades the caps 21 and 22 are positively connected by a bolt and nut 30 which extends from one cap to the other and through the shaft 11. It is to be understood that the bolt and nut 30 are associated with the caps prior to the assembly of these caps on their respective propeller blades. A two-part clamp 31 is also provided for positively and directly connecting the blades to the shaft 11, this direct connection being in addition to the indirect connection which the blades have to the shaft through the propeller casing. The parts of the clamp 31 embrace the shaft 11 and are bolted together by bolts 32 or other suitable fastening means, and this clamp 31 is provided with bearing cavities which receive flanged studs 33 and 34 fixed to the caps 21 and 22, respectively, the studs 33 and 34 being snugly fitted in the bearing cavities in the assembly and the flanges of the studs being received in a correspondingly formed part of the bearing cavity to supplement the action of the bolt and nut 30 in preventing endwise or axial displacement of the blade. At the same time these studs do not interfere with the shifting or adjusting of the blades about their longitudinal axis since they have working though snug fit in the bearing cavities of the clamp 31.

Shifting mechanism is provided for the blades 19 and 20 and includes a pair of shifting collars 40 and 41 slidably mounted on the shaft 11 exteriorly of the propeller casing. These collars 40 and 41 rotate with the shaft but are adjustable longitudinally thereon. The collar 40 is rigidly connected with one end of each member of a pair of bars 42, the bars 42 being slidably mounted in longitudinal grooves provided therefor in the shaft 11. These bars 42 extend through suitable slots provided therefor in the collar 41, the sleeve 12 and the other elements which are located on the shaft 11 between the collar 40 and a cross head 43 to which the bars 42 are connected at their ends remote from the collar 40. The cross head 43 is mounted on the shaft 11 within the propeller casing and adjacent the outer end of the shaft and is connected by links 44 and 45 with crank pins 46 and 47 respectively, the crank pin 46 being eccentrically mounted on the rings 23 of the propeller blade 19 and the crank pin 47 being eccentrically mounted on the rings 24 of the propeller blade 20. As the rings are rigidly connected with their respective propeller blades the crank pins are likewise connected thereto.

Similarly the collar 41 is rigidly connect-

ed to one end of each member of a pair of bars 50 slidably received in longitudinal grooves provided therefor in the shaft 11. Of course the grooves which receive the bars 50 are angularly spaced from the grooves which receive the bars 42. Like the bars 42 the bars 50 extend through openings or slots provided in all the elements which are located on the shaft 11 between the collar 41 and a cross head 53 to which the bars are rigidly connected at their ends remote from the collar 41. The cross head 53 is mounted for sliding adjustment on the shaft 11 and is arranged in the propeller casing 15 at the inner end thereof. Links 54 and 55 serve to connect the cross head with crank pins 56 and 57, respectively, the crank pin 56 being mounted on the rings 23 and the crank pin 57 being mounted on the rings 24. The crank pins 56 and 57 are angularly spaced from the crank pins 46 and 47 and preferably are at an angular distance of approximately 90° therefrom. The angular distance which the pins are spaced from each other may be varied as may be found desirable.

Controlling means is provided for the shifting mechanism and may comprise a yoke 60 pivotally mounted on a bracket 61 and connected by curved links 62 and 63 to the trunnions of bands or rings 64 and 65 operating in the peripheral grooves of the collars 40 and 41, respectively. A control rod 66 extending from any convenient point of control and susceptible of automatic or manual operation is pivotally connected with the yoke as at 67. With this arrangement the collars may be shifted on the shaft irrespective of whether or not the shaft is rotated since the bands 64 and 65 are loosely fitted in the peripheral grooves of the collars 40 and 41.

With the invention as thus far described the pitch of the blades 19 and 20 of the propeller may be varied as desired irrespective of the rate of rotation of the propeller shaft. In order to effect variation of the pitch of the propeller blades it is only necessary that the control rod 66 be suitably actuated. As above suggested this rod 66 may be actuated manually or may be actuated by suitable automatic mechanism as will hereinafter more fully appear. When the rod 66 is actuated it will move the yoke 60 and if the yoke 60 is moved in the direction indicated by the arrow in Figure 2 the yoke will serve in turn to spread the collars 40 and 41 that is to move these collars away from each other on the shaft, as indicated by the arrows a. The bars 42 and 50 partake of the motion of the collars 40 and 41 respectively and transmit the motion of these collars to the cross heads 43 and 53 respectively. The motion of the cross heads 43 and 53 is in turn transmitted to the propeller blades by virtue of the links 44 and 45 and the links 54 and

55, these links coacting with the crank pins as previously described. The propellers being mounted on ball bearings may be readily shifted so as to effect the desired variation 5 in the pitch of the blades but at the same time the propeller blades are positively rotated by the propeller shaft so as to exert the desired driving or lifting effect.

In Figure 5 the invention is shown organized 10 with an aeroplane so as to maintain the lateral stability thereof and for this purpose a propeller such as shown in Figures 1 to 4 and previously described is mounted at each side of the plane, the propellers being 15 arranged at each side of the plane and also being arranged to rotate about a vertical axis so that the blades exert a lifting effect. The propellers are designated at 75 and 76 and as they are in all respects identical with 20 the propellers herein above described no detail description is thought to be necessary. The propellers are mounted in any suitable manner upon the framework of the plane which is designated generally at 77. At the 25 center of the plane and intermediate the propellers 75 and 76 a pendulously mounted body 80 is provided and is pivotally supported, as at 81, on the framework of the plane. An arm 82 depends from the center 30 to the lower side of this body 80 and this arm 82 is connected by means of rods 83 and 84 to levers 85 and 86 respectively, the levers being also respectively connected to the 35 controlling rods 66 of the propellers 75 and 76 respectively.

With this arrangement when the lateral 40 stability of the plane is disturbed the body or frame of the plane will shift relatively of the pendulum 80 and this will effect an adjustment of the controlling rods 66 which will in turn vary the pitch of the propeller 45 blades in the manner herein-above described so as to increase the lifting effect of one propulsion means and decrease the lifting effect of the other pulsion means whereby to 50 overcome the disturbing influence and thus maintain the lateral stability of the plane. This action occurs automatically and occurs as may be necessary to preserve lateral stability. It is to be noted also that by actuating the propeller 66 to the necessary degree 55 that the thrust of the propeller blades may be reversed. This feature is of special advantage in landing or in controlling an airship of the Zeppelin type.

I claim:

1. In a flying machine, a propeller shaft, a casing mounted on and constrained to rotate with the shaft, propeller blades, means 60 for mounting the blades on the casing so as to constrain them to rotate with the casing while leaving them free to be shifted to vary their pitch, said mounting means including

a cap for each blade, a series of rings connected to each cap, a web for each ring, said webs and said rings having registering grooves and ball bearings received in the registering grooves, means for preventing axial displacement of the blades and for directly connecting the same to the shaft 70 by leaving the same free to be shifted including a bolt connecting the caps, a two-part clamp embracing the shaft and extending between the caps and having bearing cavities and a flanged stud carried by each 75 cap and received in the adjacent bearing cavities of the clamp.

2. In a flying machine, a propeller shaft, a casing mounted on and constrained to rotate with the shaft, a pair of propeller blades, means for mounting the blades on the casing so as to constrain them to rotate with the casing while leaving them free to be shifted angularly around their longitudinal axes whereby they vary the pitch of the blades and shifting mechanism for said blades including a pair of collars slidably mounted on the propeller shaft exteriorly of the casing, a pair of cross heads arranged within the casing, a pair of bars connecting each collar with its cross head, said bars being slidably mounted on the propeller shaft, a pair of crank pins of opposite throw carried by each blade, and a pair of links between each cross head and the crank pins, the members of each pair of links being connected to its cross head and to the members of the pairs of crank pins on the several blades.

3. In a flying machine, a propeller shaft, a casing mounted on and constrained to rotate with the shaft, a pair of propeller blades, means for mounting the blades on the casing so as to constrain them to rotate with the casing while leaving them free to be shifted angularly around their longitudinal axes whereby they vary the pitch of the blades and shifting mechanism for said blades including a pair of collars slidably mounted on the propeller shaft exteriorly of the casing, a pair of cross heads arranged within the casing, a pair of bars connecting each collar with its cross head, said bars being slidably mounted on the propeller shaft, a pair of crank pins of opposite throw carried by each blade, a pair of links between each cross head and the crank pins, the members of each pair of links being connected to its cross head and to the members of the pairs of crank pins on the several blades, and controlling means cooperating with the collars for simultaneously shifting them in opposite directions on said shaft.

JOHN ALYUSIOUS LEHNERT.
